UNITED STATES PATENT OFFICE.

ALFRED C. STEWART, OF LOS ANGELES, CALIFORNIA.

THROTTLE FOR CARBURETERS.

2,114,363.

Specification of Letters Patent. Patented Oct. 20, 1914.

Application filed September 16, 1913. Serial No. 790,015.

To all whom it may concern:

Be it known that I, ALFRED C. STEWART, a citizen of the United States, residing at Los Angeles, in the county of Los Angeles and State of California, have invented a new and useful Throttle for Carbureters, of which the following is a specification.

This invention relates to means for throttling or cutting off the supply of mixture from a carbureter to the inlet of an internal combustion engine, and the invention is particularly intended for use with heavy fuels which are liable to be deposited or separated from the mixture in passing from the carbureter to the engine. This depositing action is generally most marked when the velocity of the mixture is checked by the throttle.

The main object of the present invention is to provide means for taking up the heavy fuel deposited at the throttle, and mixing it with the air passing to the engine.

Other objects of the invention will appear hereinafter.

The accompanying drawings illustrate an embodiment of the invention, and referring thereto:

Figure 1 is a horizontal section of the throttle and the carbureter on the line a^1-a^1 , Fig. 2. Fig. 2 is a vertical section of the throttle with the carbureter attached thereto, the carbureter being shown partly in elevation. Fig. 3 is a section on line a^3-a^3 , Fig. 2.

1 designates the casing of the throttle formed as a vertical tubular member having an enlargement 2 at its lower end, and closed bottom 3. Said tubular casing 1 opens at its upper end into a chamber 4 which extends laterally and communicates with outlet of carbureter or device 5 for supplying definite measured quantities of oil and air, such carbureter being of any usual or suitable construction and being provided with an oil inlet 6, with an air inlet 7, and with any usual or suitable means for causing a definite amount of oil to be drawn in with the air passing from the inlet 7 to the outlet 8 of the carbureter. A pipe 10 extends from the top of the chamber 4 to the inlet of the engine. The tubular throttle member 12 slides vertically into the lower end portion of the pipe 10 and is provided at its lower end with an outwardly extending flange 14 co-operating with the bottom member 3 of the casing 1 of the

throttle to control the passage of mixture from the interior of the casing 1 to the interior of the tubular member 12. The co-operating portions of the flange 14 and bottom member 3 are serrated or provided with annular ridges 15 so that the air and oil in passing between the said parts will be forced to pursue a tortuous course. Suitable means may be provided for operating member 12, for example, a crank 18 on a shaft 17 mounted in bearings in casing 1, said crank carrying a pin 19 engaging in a neck 20 on the outside of tubular member 12 and shaft 17 carrying an arm 22 connected to any suitable means for operating the throttle.

For use with heavy oils it is desirable to provide means for heating the casing 1 and for this purpose an inclosing jacket 25 may be provided around the casing 1, said jacket being secured to the bottom of the top chamber 4, and provided with inlet and outlet connections or pipes 27 and 28 whereby a stream or current of heating fluid may be passed through the space 30 between said jacket and casing 1. Said fluid may consist for example, of the exhaust from the internal combustion engine, which draws its supply from the pipe 10.

The operation is as follows: Suction from the engine exerted through the pipe 10 operates when the throttle 12 is opened, to draw air together with oil through the carbureter device 5, and the chamber 4 to the vertical tubular chamber within the casing 1 of the throttle, said chamber being vertical. Any of the heavy oil which is not retained by the air and is deposited therefrom descends to the bottom of the chamber 2 and collects on the bottom plate 3 thereof. The air passing between the flange 14 near the bottom of the outlet member 12 and the bottom plate 3 is brought into effective contact with this oil collected on the bottom plate so as to take the oil up again, and mixes it with the air, carrying it forward, through the pipe 10, to the engine. The serrations 15 have an important function in this connection, in that the oil in being deposited on and borne across the edge of these serrations is more finely atomized and more effectively brought into contact with the air, the tortuous path for the air presented by the serrations also aiding in the mixing action. The heating medium such as exhaust gases or other heating agents in the

outer jacket 25 cause the casing 1 and bottom plate 3 thereof to be heated so as to bring the oil deposited from the mixture to the proper temperature required for effective vaporizing and carbureting action.

What I claim is:

1. In a throttle for carbureters, a vertically extending tubular casing having a closed bottom, means for supplying mixture of oil and air to the upper part of said casing, said casing having an outlet at its top, and a tubular throttle member slideable vertically in the outlet of said casing, and extending down within and spaced from the said tubular casing to form a passage wherein the mixture may pass from the said mixture supplying means downwardly between said casing and throttle member and upwardly within said throttle member, and means on the bottom of said throttle member coöperating with the bottom of the casing to cause a tortuous passage of mixture from the casing to the interior of the throttle member.
2. In a throttle for carbureters, a vertically extending casing having closed bottom, means for supplying a mixture of oil and air to the upper part of said casing, and a throttle member movable vertically in said casing and coöperating with the bottom of the casing to control the passage of

mixture from the casing, the coöperating parts of the throttle member and casing bottom having corresponding serrations, forming a tortuous passage when the throttle is opened. 35

3. In a throttle for carbureters, a vertically extending tubular casing having a closed bottom, means for supplying mixture of oil and air to the upper part of said casing, said casing having an outlet at its top, a tubular throttle member slideable vertically in the outlet of said casing, and extending down within and spaced from the said tubular casing to form a passage 45 wherein the mixture may pass from the said mixture supplying means downwardly between said casing and throttle member and upwardly within said throttle member, said throttle member coöperating with the bottom of the casing to control the passage of mixture from the casing to the interior of the throttle member, a heating chamber surrounding said tubular casing, and means for supplying heating agent to said chamber. 50

In testimony whereof, I have hereunto set my hand at Los Angeles, California, this 27th day of August, 1913.

ALFRED C. STEWART.
